UNITED STATES PATENT OFFICE.

LOUIS E. F. WACHTER, OF NEW YORK, N. Y., ASSIGNOR TO STAR WATCH CASE CO., OF LUDINGTON, MICHIGAN.

WATCH-PENDANT.

1,383,884.

Specification of Letters Patent. Patented July 5, 1921.

Application filed August 3, 1920. Serial No. 401,044.

To all whom it may concern:

Be it known that I, LOUIS E. F. WACHTER, a citizen of the United States, residing at New York, in the county of New York and State of New York, have invented certain new and useful Improvements in Watch-Pendants, of which the following is a specification.

My invention relates to certain new and useful improvements in watch pendants, and the principal object of my invention is to produce a construction in which deep openings in the pendant may be used for the ends of the bow, and also to enable a bow of such strength to be used to prevent the ends of the bow coming out of the recesses either by the bending of the bow or the springing of the sides, and also to provide means whereby when desired the bow may be readily disconnected from the pendant and removed without the necessity of bending or springing the bow.

With these and other objects in view my invention consists in certain constructions, combinations and arrangements of parts several forms of which will be first described in connection with the accompanying drawing and then the invention particularly pointed out in the appended claim.

Referring to the drawing wherein I show several forms of this invention and wherein the same part is designated by the same reference numeral wherever it occurs,

Figure 1 is a central longitudinal section through a pendant employing my invention with parts shown in elevation;

Fig. 2 is a central longitudinal section through a slightly modified form of construction from that shown in Fig. 1;

Fig. 3 is a central longitudinal section through a pendant showing a still further modification in which the bow is provided with ball ends;

Fig. 4 is a sectional longitudinal section through a pendant covering another modification in which the bow is also provided with ball ends, and

Fig. 5 is a plan view of one member forming the pendant.

In Fig. 1 the pendant comprises a body portion 10 centrally bored to receive the stem of the watch. Formed on this body portion is a collar 11 of any desired shape, said collar being located intermediate the

ends of the body portion. Above the collar 55 the body portion is shown as slightly enlarged at 12, and then at its upper end provided with a reduced screw-threaded portion 14. Mounted on the body portion and resting with its lower surface on the upper 60 surface of the collar 11 is a ring 15 shown in detail in Fig. 5, this ring being provided at diametrically opposite sides with the semicircular depressions 16. 17 is a second ring similar in construction and shape to 65 the ring 15. The rings 15 and 17 are together of such a thickness as to equal the height of the enlarged portion 12 of the pendant and are mounted thereon.

18 is a nut threaded to engage the threaded portion 14 of the pendant and hold the rings 15 and 17 securely in position. In assembling the parts the ring 15 is first placed over the portion 12 with its lower surface resting against the collar 11. The 70 ends 19 of the bow 20 are then placed within the depressions 16 while the rings 15 and 17 are separated and then the two rings brought together. Then by screwing the nut 75 18 on to the threaded portion 17 and turning it down tight the parts will be securely held in position. It will thus be seen that the grooves 16 may be made of ample depth to give the ends of the bow ample bearing surface, and that the body of the bow can 80 be of ample thickness to prevent any springing of the bow which would permit of the ends 19 coming out of the bearings 16 in the rings 15.

In the modification shown in Fig. 2 the 90 body portion of the pendant is formed with a flange 21 in which are formed the bearing grooves for the ends 19 of the bow 20.

22 is a ring provided with grooves to form the other half of the bearings for the ends 95 19. This ring is held in position by a nut 23 as described in connection with the form shown in Fig. 1. It will be seen that the only difference between the forms shown in Figs. 1 and 2 is that in the construction 100 shown in Fig. 2 one less part is used.

In Fig. 3 the pendant comprises the body portion 10 having the collar 11 formed integral with the body portion. Resting upon the top surface of this collar is a ring 24 105 having depressions 25 formed on diametrically opposite edges to form bearings for the ends of the bow 26, the ends of the bow in

this case being shown as formed into balls 27, and the bearings 25 in the collar 24 being of a shape to partially surround the balls.

28 is a second collar similar in shape to the 5 collar 24 and having corresponding depressions 25 in opposite sides of its circumference, so that the two depressions will together form complete bearings for the balls 27 of the bow 26.

10 The pendant is provided, as in Figs. 1 and 2, with a nut 29 to hold the rings 24 and 28 together, and thus lock the balls 27 on the ends of the bow in their bearing sockets.

In Fig. 4 I have shown a construction very 15 similar to Fig. 3, in which the pendant comprises the body portion 10 and has a collar 11 thereon, on the upper surface of which is mounted the ring 24 having the depressions 25 in opposite sides thereof for the 20 balls 27 on the ends of the bow 26.

I also provide a second ring 28 having 25 depressions corresponding to the depressions 25 in the ring 24, the two rings being held together by the nut 29 screwed on the threaded upper end of the body portion 10 of the pendant.

It will be understood that the balls may be 30 omitted from the ends of the bows in the constructions shown in Figs. 3 and 4, and also that such balls may be used if desired in connection with the constructions shown in Figs. 1 and 2.

It is to be noted however that in all the 35 constructions shown the bearings for the ends of the bow are made in two halves into which the ends of the bow may be inserted without springing the bow or changing the shape of the bow after the ends are in place, and then the two halves secured into posi-

tion to form bearings for the ends of the 40 bow. Also that a crown may be applied to the pendant with a portion overlapping the outer surface of the nut or ring 18, 23, or 29, which ring will then act as a guide to the crown in its revolutions.

45 Considerable variation of the details as described herein may be resorted to without departure from the spirit of the invention which is to be construed in the light of the following claim.

Having thus described my invention what I claim as new and desire to secure by Letters Patent is:

A watch pendant, comprising, in combination, a body portion having a plane upper 55 surface and comprising semi-spherical bearing projections extending diametrically from the main portion thereof, said projections each having a substantially semi-spherical depression in its plane surface, a cylindrical 60 portion extending above said plane surface, a removable body portion having a plane surface adapted to fit on said first named surface, and bearing projections and depressions to register with the first named bearing 65 projections and depressions, said removable portion fitting over said cylindrical portion and a cylindrical retaining ring secured to the projecting end of said cylindrical portion to hold the pendant in assembly, and 70 providing an outwardly cylindrical surface standing above the assembled pendant.

In testimony whereof I affix my signature in the presence of two witnesses.

LOUIS E. F. WACHTER.

Witnesses:

JOHN DARBY,
H. MUCHMORE.
